UNITED STATES PATENT OFFICE.

ARTHUR H. ADAMS, OF SPARKILL, NEW YORK, ASSIGNOR TO WESTERN ELECTRIC COMPANY, INCORPORATED, OF NEW YORK, N. Y., A CORPORATION OF NEW YORK.

CIRCUIT-CHANGING SWITCH.

1,266,190.

Specification of Letters Patent. Patented May 14, 1918.

Application filed December 9, 1916. Serial No. 136,079.

To all whom it may concern:

Be it known that I, ARTHUR H. ADAMS, a citizen of the United States, residing at Sparkill, in the county of Rockland and State of New York, have invented certain new and useful Improvements in Circuit-Changing Switches, of which the following is a full, clear, concise, and exact description.

10 This invention relates to automatic circuit changing switches of the type in which an operating member is adapted to be moved to a plurality of positions in each of which certain circuit changes are accomplished. 15 The embodiment of the invention disclosed herein is designed more particularly for use as a register-controller in automatic telephone systems.

The object of the present invention is to 20 provide a switch of this character which is quick-acting, accurate in operation, durable, and has few contacts.

The main feature of the present invention is the use of an electromagnetically controlled escapement mechanism to control 25 contact springs of the switch.

The above and other features of this invention will be set forth in the following description and claims.

30 Referring to the drawings, Figure 1 is a plan view of two switches mounted on a common shaft, one of said switches being partially in section, and the mechanism for winding up their spring motors. Fig. 2 is a 35 side elevation of the complete switch shown in Fig. 1, with a portion of the frame broken away to more clearly disclose the escapement mechanism. Fig. 3 is a front view of the toothed wheel and the escapement pawls.

40 Referring to the drawings, 1 represents a frame having upwardly-extending portions 2 and 3', apertured to form bearings for the shaft 3. An escapement wheel 4 is rotatably mounted on the shaft 3, between collars 16 and 35, which are rigidly fixed to the shaft 3. A number of equally spaced notches 25 of various depths are arranged about the periphery of the wheel 4, thus forming a plurality of teeth 24. The wheel moves in the 45 direction indicated by the arrow (Fig. 2). Between the first tooth 26 and the last tooth 33, a double space 32 is provided to allow the wheel to be stopped without having any of its teeth in engagement with the escape- 50 ment mechanism. A pin 18 extends from one side of the wheel 4. A spiral spring 11, wound around shaft 3 and having one of its ends attached to the wheel 4 and its other end attached to collar 35, operates to drive the toothed wheel 4. Lever 7 is secured to the armature 6 of the magnet 5. The armature is pivoted to the frame 1. Lever 7 has the escapement pawls 22 and 23, (Fig. 3) extending from one end, which engages the toothed wheel 4, and controlling the escape- 55 ment thereof.

Stationary contact springs 28, 30 and 27 and movable contact springs 29 and 31 are insulatedly attached to the frame by means of screws. Connected to these springs are 70 the circuits (not shown) controlled by the switch. As shown in Fig. 1, the movable springs 29 and 31 are arranged to be moved by lever 7. When the armature 6 is completely retracted, the lever moves contact 75 spring 29 into engagement with contact spring 28, and when the armature 6 is completely attracted, lever 7 moves contact spring 31 into engagement with contact spring 27. 80

In the present embodiment of the invention, there are two positions in which the lever 7 can be stopped in its attracted movement, and two positions in its retracted movement. In each of these positions, certain circuit changes are produced. When the armature 6 is attracted, the escapement pawl 22 is drawn out of engagement with a tooth, and escapement pawl 23 is drawn into engagement with the next tooth of the 90 wheel 4, which is rotated by means of spring 11. If the notch between these teeth is of sufficient depth to allow the escapement pawl 22 to pass, lever 7 is moved far enough to the right so as to close contact springs 31 95 and 27, and allow contact spring 29 to come into contact with the stationary spring 30. If the notch is not of sufficient depth, the escapement pawl 22 engages the side of the wheel 4 and does not allow lever 7 to be moved far enough to close contact springs 31 and 27 and to allow contact spring 29 to come into contact with contact spring 30. When relay 5 is deenergized, armature 6 is retracted and the tooth in engagement with escapement pawl 22 moves into engagement with escapement pawl 23. If the space between this tooth and the preceding tooth 100 105

is of sufficient depth to allow the escapement pawl 23 to pass, the lever 7 moves spring 29 into engagement with spring 28. If the notch is not of sufficient depth, the escapement pawl 22 will engage the side of the toothed wheel 4 and will prevent the complete attraction of the armature and the lever 7, thus preventing the closure of springs 29 and 30.

- 10 When the last tooth 33 of the toothed wheel 4 has been rotated out of engagement with escapement pawl 23, the wheel is rotated until the pin 18, extending from the side of the wheel, engages with projection 17 of the collar 16, which is attached to the shaft 3, and stops the wheel in a position so that the escapement pawls 22 and 23 are held midway of the double space between the last tooth 33 and the first tooth 26. In this position, a circuit (not shown) is closed for operating the clutch magnet of the mechanism to wind up spring 11. This mechanism consists of a disk 12 attached to the shaft 3, a clutch magnet 15 attached to the frame, and a disk 13 driven by a constantly rotating shaft 14. Disk 13 and shaft 14 are held in position by a supporting structure (not shown). When magnet 15 is energized, disk 12 is attracted and brought into contact with disk 13 and drives shaft 3 to wind up the spring 11. Pawl 20 and ratchet wheel 21 are provided to prevent the shaft from rotating backward. As the shaft 3 is rotated, the collar 16 with the pin 18 is also rotated, and the toothed wheel 4 allowed to escape until the first tooth comes into engagement with the escapement pawl 23, in which position the wheel is held during the winding up of the spring and until magnet 5 is again energized to start another cycle of operation of the switch. The circuit of magnet 15 is opened, by any well-known means, when a complete rotation of the shaft has been made to wind up spring 11.
- 45 From the above description it is evident that by varying the depth of the notches between the teeth and the number of teeth any desired combination of circuit changes can be produced by the switch.
- 50 Fig. 1 also shows the mounting and the common drive of a set of switches similar to that described above. Such an arrangement is especially adapted to be used for a register controller. A switch for each digit of the calling number is used. The escapement magnet of each switch is adapted to be operated by impulses sent over the calling line for the particular digit to which the switch is used. For example, if the called number is 7234 the escapement magnet of the 1000's digit switch is operated to escape its toothed wheel seven steps, the escapement magnet of the 100's digit switch is operated to escape its toothed wheel two steps, the escapement magnet of the 10's

digit switch is operated to escape its toothed wheel three steps, and the escapement magnet of the units digit switch is operated to escape its toothed wheel four steps. The contact springs of each switch are operated under the control of its respective toothed wheel to control circuits leading from the contact springs to establish the connection to the called line. The shaft which is common to all the switches serves to wind up the springs of each individual switch, when the last digit switch, namely the units switch, has completed its operation.

What is claimed is:

1. In a circuit changing switch, a plurality of contact springs, an operating member for bringing certain of said contact springs into engagement with each other, means for actuating said operating member, and an escapement mechanism for controlling said operating member actuated by said operating member. 80
2. In a circuit changing switch, a plurality of stationary contact springs and a plurality of movable contact springs, an operating member arranged to bring certain of said movable contacts into engagement with certain of said stationary contacts, means for moving said operating member, and an escapement mechanism for controlling the said operating member actuated by said operating member. 90
3. In a circuit changing switch, a plurality of contact springs, an operating member arranged to bring certain of said contact springs into engagement with each other, means for actuating said operating member, a shaft, a toothed wheel loosely mounted thereon, means for rotating said wheel, said wheel being arranged to control said operating member. 100
4. In a circuit changing switch, a plurality of contact springs, an operating member arranged to bring certain of said contact springs into engagement with each other, means for actuating said operating member, a shaft, a toothed wheel loosely mounted thereon, means for rotating said wheel, and means associated with said operating member for controlling the rotation of said wheel, said wheel being arranged to control said operating member. 110
5. In a circuit changing switch, a plurality of contact springs, an operating member arranged to bring certain of said contact springs into engagement with each other, means for actuating said operating member, a shaft, a toothed wheel loosely mounted thereon, means for rotating said wheel, and escapement pawls connected to said operating member for controlling the rotation of said wheel, said wheel being arranged to control said operating member. 120
6. In a circuit changing switch, a plurality of contact springs, an operating mem- 130

ber arranged to bring certain of said contact springs into engagement with each other, means for actuating said operating member, a rotatable shaft, a toothed wheel loosely mounted thereon and being arranged to control said operating member, a spring for rotating said wheel, and means for winding

up said spring after said wheel has completed a cycle of operation.

In witness whereof, I hereunto subscribe my name this second day of December, A. D. 1916.

ARTHUR H. ADAMS.
